UNITED STATES PATENT OFFICE.

GURTH F. CHAMBERS, OF LONDON, ONTARIO, CANADA, ASSIGNOR TO CANADA BISCUIT COMPANY, LIMITED, A CORPORATION OF ONTARIO, CANADA.

DESIGN FOR A BISCUIT.

Application filed May 17, 1927. Serial No. 22,011. Term of patent 3½ years.

To all whom it may concern:

Be it known that I, GURTH F. CHAMBERS, a subject of the King of England, and resident of the city of London, Ontario, Dominion of Canada, have invented a new, original, and ornamental Design for a Biscuit, of which the following is a specification, reference being had to the accompanying drawing, forming part thereof.

Fig. 1 is a plan view of the top of the biscuit;

Fig. 2 is an edge view of the biscuit; Fig. 3 is a plan view of the bottom of the biscuit, illustrating my new and ornamental design.

I claim:

The ornamental design for a biscuit as shown.

GURTH F. CHAMBERS.
